(57) **CLAIM**

The ornamental design for a “kit for artificial stream for gardens,” as shown and described.

DESCRIPTION

FIG. 1 is a top view showing one component piece of the present invention;

FIG. 2 is a bottom view showing one component piece of the present invention;

FIG. 3 is a rear view showing one component piece of the present invention;

FIG. 4 is a front view showing one component piece of the present invention;

FIG. 5 is a right side view showing one component piece of the present invention;

FIG. 6 is a left side view showing one component piece of the present invention;

FIG. 7 is a top view showing a second component piece of the present invention;

FIG. 8 is a bottom view showing a second component piece of the present invention;

FIG. 9 is a right side view showing a second component piece of the present invention;

FIG. 10 is a left side or front view showing a second component piece of the present invention;

FIG. 11 is a rear view showing a second component piece of the present invention;

FIG. 12 is a top view showing a second component piece of the present invention;

FIG. 13 is a bottom view showing a third component piece of the present invention;

FIG. 14 is a rear view showing a third component piece of the present invention;

FIG. 15 is a front view showing a third component piece of the present invention;

FIG. 16 is a right or left side view showing a third component piece of the present invention;

FIG. 17 is a top view showing a fourth component piece of the present invention;

FIG. 18 is a bottom view showing a fourth component piece of the present invention;

FIG. 19 is a front or rear view showing a fourth component piece of the present invention;

FIG. 20 is a right side view showing a fourth component piece of the present invention;

FIG. 21 is a left side view showing a fourth component piece of the present invention;

FIG. 22 is a top view showing a fifth component piece of the present invention;

FIG. 23 is a bottom view showing a fifth component piece of the present invention;

FIG. 24 is a front or rear view showing a fifth component piece of the present invention;

FIG. 25 is a right or left side view showing a fifth component piece of the present invention;

FIG. 26 is a top down view of the first component in an environment with the broken lines forming no part of the claimed design; and,

FIG. 27 is a top down view of the first component in an environment with the broken lines forming no part of the claimed design.
